UNITED STATES PATENT OFFICE

119,962

DESIGN FOR A DISPLAY DEVICE ENSEMBLE

Paul M. Kleinwachter, Chicago, Ill.

Application February 5, 1940, Serial No. 90,036

Term of patent 7 years

To all whom it may concern:

Be it known that I, Paul M. Kleinwachter, a citizen of the United States, residing at Chicago, in the county of Cook and State of Illinois, have invented a new, original, and ornamental Design for a Display Device Ensemble, of which the following is a specification, reference being had to the accompanying drawing, forming a part thereof.

Figure 1 is a perspective view of the complete display device ensemble, showing my design.

Fig. 2 is a similar perspective view showing the front guard of the ensemble removed.

Fig. 3 is a top plan view of the complete ensemble on a slightly reduced scale.

Fig. 4 is an end elevational view of the ensemble looking at the right end of Fig. 3.

I claim:

The ornamental design for a display device ensemble, substantially as shown.

PAUL M. KLEINWACHTER.
